UNITED STATES PATENT OFFICE.

JAN BRAKSATOR, OF CLEVELAND, OHIO.

DIRECTION-SIGNALING DEVICE.

1,287,854.

Specification of Letters Patent. Patented Dec. 17, 1918.

Application filed September 2, 1914. Serial No. 859,847.

To all whom it may concern:

Be it known that I, JAN BRAKSATOR, a subject of the King of Hungary, residing at Cleveland, in the county of Cuyahoga and 5 State of Ohio, have invented a new and useful Improvement in Direction-Signaling Devices, of which the following is a specification, the principle of the invention being herein explained and the best mode in which 10 I have contemplated applying that principle, so as to distinguish it from other inventions.

My invention is intended to furnish at a glance information as to the direction in 15 which a moving vehicle is going to continue. Accordingly the object is to contribute toward safety and facilitate the execution of traffic regulations. More particularly the device is designed to signal in front and to 20 the rear, in daytime and at night-time whether the vehicle is next to move straight ahead or to the right or left.

The inventive conception is associated with means which are hereinafter explained 25 and variously combined in the claim. While the annexed drawing and particular description thereof, set forth in detail a preferred and modified form embodying my invention, it should be understood that such 30 means only exemplify some of the many diversified mechanical forms with which the principle of my invention may be properly applied.

Adverting to the drawings:

35 Figure I is an elevation of an automobile equipped with the preferred form of my invention.

Fig. II is an enlarged partial view in part section and part elevation.

40 Fig. III is a section on line III—III of Fig. II looking in the direction of the arrows.

Fig. IV is a section on line IV—IV of Fig. II looking in the direction of the arrow.

45 The four views to which reference is to be had, will be noticed as associated with the body A of an automobile involving a flooring a', foot board a², seat a³ and wind-shield a⁵. The dash a⁴ is provided above with an 50 opening with which a bearing a⁷ registers. Operatively mounted in the usual manner, is the steering post B which carries on its upper end a steering wheel b'.

Supported upon the front of the dash a⁴ 55 to inclose the opening a⁶ is an oblong compartment C having a glass inclosed front c'

and above the same a lamp c² surmounted by a shade c³. Mounted interiorly of the compartment C in the plane of the opening a⁶ is a horizontal shaft c⁴. Keyed to one 60 extremity of the shaft is a beveled pinion c⁵. Also mounted upon the shaft c⁴ between its pair of bearings c⁶ is a triangular hub c⁷ as best seen in Figs. I and III. Secured to each of the faces c⁸ of the hub by means of 65 screws c⁹ or any other suitable means is an indicating plate c¹⁰. The three plates c¹⁰ have fashioned upon their outer sides respectively the letters S, R and L to denote straight ahead, right and left. In Fig. 3 70 that one of the plates c¹⁰ which is to denote straight ahead, is shown in an up-right position so as to be entirely visible through the glass c'.

Embracing the steering post B in intersection with the plane of the axis of the shaft c⁴ is a bracket D. This bracket is provided with a bearing d' rearwardly in line with the axis of the post B, and a second horizontal bearing d² on a level with the 80 axis of the shaft c⁴. Another bracket E is clamped to the steering post B above, by means of a bolt and nut combination e'. The bracket E projects rearwardly in the form of a segment e² at opposite extremities 85 of which the letters R and L are placed in correspondence with the right and left side of the driver of the vehicle. The center of the bracket E, with reference to the arc of the segment e², is provided with an opening 90 e³ intended to serve as a bearing in line with the bearing d'.

A shaft F is mounted for movement in the bearings a⁷ and d². Rearwardly of the bearing d², the shaft F carries a beveled pinion 95 f'. The shaft F further extends through the opening a⁶ and also carries upon this free extremity another beveled pinion f² adapted to mesh with the pinion c⁵ in the compartment C. A rod G is mounted for 100 movement in the bearings d' and e³. Just above the bearing d' the rod carries a beveled pinion g' so as to lie in mesh with the pinion f'. The upper extremity of the rod G has secured to it a lever g² adapted to be 105 moved across the segment e² as is well indicated in Fig. 4.

Describing now the operation of one complete portion of my device, which is intended as a signal to persons ahead of the vehicle, the actuation of the parts is in the 110 following sequence:

Under ordinary conditions of running, the lever g^2 will be kept in its medial position in consequence of which the plate c^{10} , having the letter S depicted upon it will 5 be in the upright readable position as shown in Figs. I and III. When the driver is intending to presently turn to the right he has only to move the lever g^2 to the right in the direction of the letter R upon the segment 10 e^2 whereupon the rod G, shaft F and hence the hub c^7 are rotated through an arc of 120 degrees thereby bringing that particular plate c^{10} into readable view which has upon it the letter R. Should the driver be intending 15 presently to turn to the left the operation of the lever g^2 is simply reversed as suggested in Fig. 4.

I consider it desirable moreover to make possible a simultaneous signaling at the rear 20 of the moving vehicle in response to the manipulation of the lever g^2 explained in the previous paragraph. To this end, I have arranged to have the rod G pass through the foot-board a^2 and carry upon its lower 25 extremity a beveled pinion g^3 . To the underside of the board I affix an angular bearing bracket H having a bearing h' through which the rod G extends and a transverse bearing h^2 perpendicular to the foot-board itself. To the flooring a' and foot-board a^2 30 upon the underside of their junction I fix another bearing bracket J having a bearing j' parallel with the bearing h^2 and a second bearing j^2 perpendicular to the flooring a' . A shaft K is disposed for movement in the 35 bearings h^2 and j' , to project a slight distance beyond each of the latter and carries upon its extremities beveled pinions k' and k^2 . As so arranged the beveled pinion k' 40 is in mesh with the beveled pinion g^3 . Another shaft L extends through the bearing j^2 and has fixed upon its extremity a beveled pinion l' adapted to mesh with beveled

pinion k^2 . The opposite or rear extremity of the shaft L extends into another compartment C carried upon the rear of the vehicle. In its partial rotation in opposite directions the shaft L is to perform the same function of showing a plurality of signals that the shaft F performs interiorly of the forward compartment C. It will be understood that the relation of the several beveled pinions is such that a maximum range of movement of the lever g^2 causes the hub c^7 to rotate through an arc of 240 degrees. 45 50 55

My invention being thus described with sufficient thoroughness, what I desire to secure by Letters Patent and therefor claim specifically, is:

A direction signaling device comprising 60 the combination of a compartment adapted to be carried on the front of a vehicle and having a pair of oppositely located openings, an actuating member projecting into said compartment through the rearwardly 65 located of said openings, a glass front fitted to the front opening, supporting bearings within said compartment, a shaft mounted in said bearings at right angles to said member and carrying a hub of polygonal cross 70 section so as to have flat surfaces, gearing connecting said member and shaft, a plurality of flat signal plates circumferentially secured to and projecting in different directions from said hub surfaces, said plates 75 being equispaced and adapted to swing across and assume a position substantially parallel to the other of said openings such that only one is enabled to be displayed therethrough. 80

Signed by me this 19th day of August, 1914.

JAN BRAKSATOR.
